United States Patent Office

Des. 185,847
Patented Aug. 11, 1959

185,847

WHEEL COVER

Paul H. Deesen, Rochester, and Robert Dustan, Jr., Clawson, Mich., assignors to General Motors Corporation, Detroit, Mich., a corporation of Delaware

Application January 29, 1959, Serial No. 54,380

Term of patent 7 years

(Cl. D14—30)

Figure 1 is a front elevational view of a wheel cover, showing our new design;

Figure 2 is a sectional view taken on the plane indicated by line 2—2 of Figure 1;

Figure 3 is a side elevational view; and

Figure 4 is a perspective view.

We claim:

The ornamental design for a wheel cover, substantially as shown.
